UNITED STATES PATENT OFFICE.

THOMAS A. THOMPSON, OF BUTTE, MONTANA, ASSIGNOR OF ONE-HALF TO P. J. QUINN,
OF BUTTE, MONTANA.

ENVELOP-SEALING MEANS.

1,218,494.

Specification of Letters Patent.

Patented Mar. 6, 1917.

Application filed February 23, 1916. Serial No. 80,009.

To all whom it may concern:

Be it known that I, THOMAS A. THOMPSON, a citizen of the United States, residing at Butte, in the county of Silver Bow and 5 State of Montana, have invented certain new and useful Improvements in Envelop-Sealing Means, of which the following is a specification.

The present invention appertains broadly 10 to improvements in envelopes and in particular to safety sealing means therefor.

The object of my invention is to eliminate entirely the use of adhesive in the formation of an envelop and to provide instead 15 thereof securing means of such character as will connect the flaps of the envelop together and afford at the same time sealing means for the closing flap which will preclude access to the contents of the envelop 20 without detection.

For a full understanding of the present invention, reference is to be had to the following description and the accompanying drawing, in which:

25 Figure 1 is a rear elevation of an envelop provided with the securing means forming the subject matter of this invention.

Fig. 2 is a longitudinal sectional view of the envelop taken on about the plane indicated by the line 2—2 of Fig. 1.

Figs. 3 and 4 are sectional views on the respective lines 3—3, and 4—4 of Fig. 1.

Fig. 5 is a fragmentary view showing the button or shell element of this device.

35 Fig. 6 is a similar view showing the stud element.

Fig. 7 is a detail view of the locking member mounted in the stud.

Fig. 8 is a similar view of the locking 40 member for the shell.

Throughout the following detail description, and on the several figures of the drawing, similar parts are referred to by like reference characters.

45 Referring to the drawing, the numeral 1 designates an envelop which may be constructed along conventional lines, said envelop being provided with the end flaps 2, the bottom flap 3 and the closing flap 4. 50 I do not wish to be confined to any particular shape or arrangement of these flaps as it is within the purview of the invention to attach the safety locking means herein-after to be described to said flaps in such a

manner as to eliminate the necessity of 55 using adhesive as hereinbefore premised.

To this end, and referring particularly to the type of envelop shown in Fig. 1 of the drawing, a plurality of securing devices are employed, one at each end and at the center 60 of the envelop, so disposed as to connect the end and bottom flaps together and arranged also to connect the closing flap so as to securely close the envelop against unauthorized access.

65 The securing means of this invention is of that type which when locked will be incapable of being unlocked without destruction of the envelop as by cutting it open to obtain access to the contents thereof.

70 Specifically describing the securing means above referred to, the numeral 5 designates what for the purpose of this description will be termed a stud, said member being of hollow formation and having connection with 75 the body of the envelop, as shown in Fig. 3, to the end flap 2 by flanging outwardly the base of the material. The stud is formed with a headed portion 5' which extends through the bottom flap 3 and is provided 80 with an aperture 6 opening into the hollow head of this member. Seated within the hollow head 5' is a locking member most clearly shown in Fig. 7 of the drawing, said member consisting of a spring 7 having its 85 extremities bent inwardly to form opposite yieldable or separable locking elements 8. The ends of these elements 8 are beveled for reasons which will be more clearly understood as this description proceeds. 90 The locking elements 8, as will be observed from the drawing, are juxtaposed with relation to the aperture 6 of the stud.

95 Adapted to coöperate with the headed stud 5 hereinbefore described, I provide a shell or button member 9, this element of the locking means being attached to the closing flap 4 of the envelop by flanging the material of the button as indicated at 10. The shell 9 is thus formed with an 100 opening therebeneath which is of such size as to snugly receive the headed stud 5 when the shell and stud are disposed in coöperative relation. Within the shell 9 is provided a locking member 11 most clearly 105 shown in Fig. 8 of the drawing, said member consisting of a flat strip of metal, preferably of resilient character, and secured in

the shell by clamping or crimping the outer edge of the material of said shell, as indicated at 12. It will be noted that the locking member 11 is bent intermediate its length to form a V-shaped projection, at the lower portion of which are provided opposite detents or apertures 13.

It will thus be apparent from this description that when it is desired to close the envelop or seal its contents the closing flap 4 carrying the button elements is brought into closed position and the studs 5 introduced into the openings of the shells. As the head of each stud is inserted it is guided by the wall of the button aperture so that the V-shaped projection 11 passes into the apertured head of the stud until the points 8 of the stud locking member 7 interlockingly engage in the detents 13 of the locking member 4 of the shell. This interlocking engagement by reason of the arrangement and construction of parts prevents any access to said parts which will permit of the disengagement of the locking elements. After once engaged these locking devices are not susceptible of being disengaged and hence the contents of an envelop closed by this character of sealing means is protected against being tampered with. The material of the envelop surrounding the stud is preferably formed with a depression and similar depressions being made in the flaps and surrounding the button so that the locking device will be seated as nearly flush with the outer surface of the envelop as practicable. It will be obvious that any number of these locking devices may be employed upon an envelop depending entirely upon its construction especially with reference to the formation of the envelop flaps.

Copies of this patent may be obtained for five cents each, by addressing the "Commissioner of Patents, Washington, D. C."

Having thus described my invention, what I claim as new is:

1. Securing means for envelops of the class described comprising a hollow stud, a locking member carried therein, a shell adapted to receive the stud, and holding means on said shell engageable with the locking member upon introduction of said stud into the shell. 50

2. Securing means for envelops of the class described comprising a stud, a yieldable locking member wholly received in the stud and consisting of an open ring-shaped member, a shell into which said stud is adapted to be received, and projecting means on said shell adapted to interlock with the locking member upon introduction of said stud into the shell. 55

3. Securing means for envelops of the class described comprising a stud having an apertured head, a shell adapted to receive the head, and a locking member in said shell having a V-shaped locking member projecting out of the same adapted to be received 65 in the apertured head of the stud for interlocking engagement therewith.

4. Securing means for envelops of the class described comprising a hollow stud, a locking spring seated in the head of said stud, the stud having an opening adjacent to which the locking member is disposed, a button or shell adapted to receive the stud, a locking member disposed in said button and formed with a notched projection 75 engaging in the aperture of said stud and interlocking with the stud locking member aforesaid to hold the button and stud together.

In testimony whereof I affix my signature. 80

THOMAS A. THOMPSON.
